UNITED STATES PATENT OFFICE.

WILLIAM WOOD, OF FALL RIVER, MASSACHUSETTS, ASSIGNOR TO JAMES K. LANNING,
OF FALL RIVER, MASSACHUSETTS.

HALF LAP FOR COMBING TEXTILE FIBERS.

Application filed August 6, 1923. Serial No. 655,926.

This invention relates to the art of combing yarn, and is particularly concerned with the construction and arrangement of the so-called half-laps which constitute the combing elements of a combing machine to pull or comb out the short fibers from the staple, and at the same time lay the remaining fibers lengthwise in parallelism with one another.

10. The active combing member or half-lap as heretofore made has been built up in a series of separate sections secured to a half-round shell or base, each section carrying a row of spaced needles projecting outwardly beyond the peripheral face of its supporting section. Such a construction, however, entails serious practical difficulties. If one row of needles in the forward part of the comb be injured all the sections to the 15 rearward must be removed to permit the removal and replacement of the imperfect section, and as the work of building a half-lap is a very nice and delicate operation that can properly be performed only by a 20 highly skilled and experienced workman, the loss of use of the half-lap, while it is sent away for repairs, necessitates carrying a large number of extra half-laps besides involving large expenses for repairs.

25. Furthermore, half-laps as heretofore constructed caused much trouble and loss by reason of the accumulation of flocks of lint which adhered to the surface and prevented the comb from properly performing its work.

30. With these objects in view I provide a half-lap construction comprising successive rows of spaced needles firmly supported by holding means abutting against opposite sides of the front and rear sides of the butt ends of the needles in such manner that the needle-supporting wall, on the forward or underside of the needles, retreats farther from the point or nearer to the central axis of rotation than does the supporting stock or material on the rear or upper side of the needles, by which offset the accumulation of lint in front of each row of needles is effectively prevented, probably due to the fact that the clearing brushes act more effectively to remove the lint from between the needles. Furthermore, the holding member, bed or matrix which forms the anchorage or support for each row of needles is so constructed and dimensioned, with reference to

the needle-carrying bars, that no cracks or crevices are found in the completed half-lap for the lodgement or adhesion of lint. Other features relate to the means for supporting and securing the needles in place, all of which will be described in detail in the following specification and will be defined in the annexed claims. 60

In the accompanying drawings I have illustrated different forms of construction and arrangement embodying the principles of this invention, in which:

Figure 1 is an end elevation of a half-lap constructed according to this invention and secured to its revolving support. 70

Figure 2 is a longitudinal section through said half-lap on the plane of the forward wall of the comb-retaining slot, showing the means for fastening the comb-bar or element in place. 75

Figure 3 is an end elevation of a modified form of half-lap secured to its revolving support in which common fastening or locking means are employed for all the needle bars or comb elements. 80

Figure 4 is a longitudinal section of the modification of Figure 3 on a plane coincident with the front wall of one of the comb-bar receiving slots. 85

Figure 5 is an end elevation of another modification in which the needle-carrying or comb-bar is made in longitudinal sections.

Figure 6 is a longitudinal section through the half-lap shown in Figure 5, on a plane coincident with a front wall of one of the comb-retaining slots. 90

In the practice of this invention, according to the form illustrated in Figures 1 and 2, I provide a comb-holding member or bed 1, which has approximately the form of a segment of a hollow cylinder which arcuate bed member is formed with its inner surface 2, concentric with the axis of its revolution, and with the peripheral surface of its revolving supporting shaft or shell 3. 95

In the process of manufacture, the outer or peripheral surface 4, of the supporting member 1, is described on a circle that is slightly eccentric to the axis of rotation. In Figure 1 of the drawings, the axis of rotation coincides with the point of intersection of the lines $x-x$ and $w-w$, while the center of the arc forming the outer curved surface of the comb-holding member is coinci- 100
105
110

dent with the intersection of the lines $y-y$ and $w-w$.

In the outside of the matrix or bed 1, I cut a series of longitudinal slots for the reception of the needle-carrying bars forming the comb elements. These slots or channels are inclined forwardly of the intersecting radii, that is, in the direction of revolution of the half-lap which is indicated by 10 the arrow in Figure 1.

The cutting of these slots leaves a series of longitudinal peripheral ribs 5, whose front and rear walls form the boundary of two successive slots. The outer faces of these 15 ribs are cut away so as to leave the rear edge of each rib which forms the front wall of each slot lower than the front edge of each rib which forms the rear wall of the next slot in advance or, to state it differently, the front edge of each slot is nearer to the axial center and farther from the points of its row of needles than is the rear edge of each slot, due to the lengthwise recess formed as aforesaid.

23 The comb element comprises a flat bar 6, rabbeted at its forward and outer edge to form a shallow channel for the reception of the needles 7 which are placed side by side along that portion of the bar with their outer ends uniformly spaced apart, the needles being soldered to the thin part of the bar 6, to secure them in parallelism on said bar. The needle bars and the needles are so dimensioned that the points of 30 all needles in each row, as well as all the rows of needles, are equidistant from the axial center of rotation. Owing to the inclination of successive rows of needles and to the eccentricity of the curve coincident with the high points of the ribs 5, to the axial center, the points of the needles, while moving through the same circular path of revolution, project farther and farther beyond the outer surface of the bed or matrix from the rear row to the front row of 35 needles.

40 Preferably the needle bars 6, are formed at their outer edges, where they form the rear side support for their respective rows of needles, to lie flush with the adjacent edge of the rib 5, and each comb element is made to exactly occupy or fill the slot for which it is intended so as to leave no 45 crack or crevice for the catching of lint.

50 The cutting away of the rear edge portion of each rib to cause it to lie farther from the point or nearer to the axial center than does the supporting material on the rear side of each row of needles, I have found, 55 results in producing an offset which substantially eliminates the heretofore very troublesome accumulation of lint which has usually lodged or wedged in the angle between the forward or underside of the needles and the peripheral surface of the half-lap and

from which the clearing brushes oftentimes fail to remove the lint. This offsetting of the solid material of the needle-holding matrix has proved to afford a practical solution for this trouble and constitutes an important feature of the present invention.

70 For holding the comb elements securely seated in their retaining slots, I have formed notches in the opposite ends of each needle bar 6, said notches preferably being provided with a bevelled face 6^a, engaged by the tapered end of the fastening screw 8, which is tapped into short threaded holes formed in the end walls of each slot. By 75 tightening these fastening screws each needle-bar may be properly adjusted lengthwise and anchored to the bottom of its supporting slot.

80 The half-lap is secured to its shaft or revolving support in any suitable manner as 85 by means of radial screws 9, which pass through projecting flanges 1^a, formed on the rear and front sides of the bed.

90 In Figure 3, I have illustrated a modified form of construction for securing the needle-carrying bars in the holder or bed. In this case a single fastening element is employed for anchoring the whole series of bars and comprises, as shown, an arcuate key-bar 10, provided with an inwardly extending flange 10^a, overlapping the end of the bed 12, and provided with a screw-receiving perforation intermediate of its ends through which is inserted the fastening screw 13, which is tapped into the end face of the base or bed 12. The arrangement of the needles in this case, is similar to that already shown in Figures 1 and 2.

105 It may prove to be advantageous in practice to make the needle bars in short sections so that only one short section need be replaced in case of injury, instead of the entire bar. With this end in view, I have shown in Figures 5 and 6 a construction in which the needle bars are composed of intermediate sections 20, and end sections 21, formed with abutting square ends, the sections being held in position by means of a longitudinal rod or key 22, dimensioned to be driven into the longitudinal groove 110 formed partly in the bar sections and partly in the wall of the retaining slot formed in the bed plate 23. Lengthwise displacement of the key and bar may be prevented by the use of nuts 24, on opposite ends of 115 each key.

120 For convenience in preventing the insertion of the wrong needle bar in any particular slot, the respective bars and slots may be marked with identifying letters or 125 numerals.

130 What I claim is:

1. A half-lap for combing textile fibers, embracing in its construction plural rows of spaced needles concentrically arranged

- about a common axis of revolution, and holding means therefor presenting needle-holding front and rear walls whose outer edges are unequally distant from the points of their interposed needles, the front walls being more distant than the rear walls, whereby accumulation of lint adjacent to the needles is prevented, substantially as described.
2. A half-lap for combing fibers embracing in combination a revoluble bed formed with longitudinal slots to leave intervening ribs, the edge of the rib in advance of each slot being inwardly offset with relation to the adjacent edge of the rib forming the rear side of said slot, and a needle-carrying element secured in said slot, substantially as described.
3. A half-lap for combing textile fibers embracing in its construction a revoluble integral bed member provided with a series of longitudinal slots extending obliquely to radial planes intersecting them, the forward walls of the respective slots being substantially cut away in an approximately tangential direction to make them lower than the rearward walls thereof, a needle-carrying member inserted in each slot, and means for securing the needle-carrying members detachably in position, substantially as described.
4. A half-lap for combing textile fibers embracing a revoluble segmental carrier provided with a plurality of outwardly projecting ribs separated by narrow slots, a series of needle combs snugly inserted in said slots to avoid the formation of any crevice in front of the combs, the forward exterior edge of each rib extending outwardly nearer to the points of the needles than does the rear edge of the next forward rib in contact with the needles, substantially as described.
5. In a half-lap for combing fibers, the combination of a longitudinally slotted arcuate bed provided with longitudinal slots, needle-carrying members inserted in said slots to allow the needles to project outwardly, and removable fastening means adapted to be threaded endwise into the slot in the bed to engage and lock the needle-carrying members detachably in position, substantially as described.
6. In a half-lap for combing fibers, the combination of a longitudinally slotted arcuate bed, comb elements, each comprising

a bar and a row of needles secured thereto, inserted in said slots, said bar being provided with locking recesses and longitudinally disposed fastening devices arranged to have threaded engagement in said recess and detachably lock the comb element in position, substantially as described.

7. In a half-lap for combing fiber, the combination of a longitudinally slotted arcuate bed, a series of comb-elements comprising a bar and a row of laterally projecting needles secured thereto, said bar being made in longitudinal sections and being provided with locking recesses, and means for engaging said recesses to secure said elements firmly but detachably in operative position, substantially as described.

8. In a half-lap for combing fibers, the combination of an arcuate bed provided with parallel longitudinal slots in its periphery, comb elements detachably secured in said slots, each element comprising a longitudinal bar transversely divided into sections, and needles secured transversely thereof to project laterally outward, and common locking means engaging all said sections for detachably securing said sections in operative position in said slots, substantially as described.

9. A half-lap for combing fibers, embracing in its construction a revoluble arcuate bed plate provided in its peripheral surface with longitudinal forwardly inclined slots, comb elements, each comprising a longitudinal bar with a row of needles secured on its forward side to project beyond the outside edge of said bar, said comb elements being snugly secured in said slots with their outer edges flush with the rear edges of said slots, and outwardly offset with relation to the forward edges of the corresponding slots, substantially as described.

10. A comb member embracing a flat bar longitudinally grooved inwardly from its edge to form a needle-receiving recess lengthwise of the bar, and a row of transversely disposed pointed needles secured side by side in said recess with their tapered points projecting beyond the edge of the bar, whereby the comb element is adapted to snugly fit into and completely fill a receiving slot in the arcuate bed of the half-lap, substantially as described.

In witness whereof, I have subscribed the above specification.

WILLIAM WOOD.
